S. Caserto

By *O. Randolph Jr. Atty*

UNITED STATES PATENT OFFICE.

SAM CASERTO, OF STOLLINGS, WEST VIRGINIA.

MINER'S LAMP.

1,359,330.

Specification of Letters Patent. Patented Nov. 16, 1920.

Application filed January 7, 1920. Serial No. 349,865.

To all whom it may concern:

Be it known that I, SAM CASERTO, a subject of the King of Italy, residing at Stollings, in the county of Logan and State of West Virginia, have invented certain new and useful Improvements in Miners' Lamps; and I do hereby declare the following to be a full, clear, and exact description of the invention, such as will enable others skilled in the art to which it appertains to make and use the same.

This invention relates to new and useful improvements in miners' lamps of the carbide burning type and has for one of its objects the provision of means for receiving and supporting electrical illuminating means, so that said means can be employed for illumination while refilling the lamp with carbide, thereby obviating the necessity of conducting such work in the dark.

Another object of the invention is the provision of a miner's lamp of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention reference is to be had to the following description and accompanying drawing, in which:

Figure 1 is a side elevation of a miner's lamp constructed in accordance with my invention.

Fig. 2 is a front elevation of the same.

Fig. 3 is a longitudinal sectional view illustrating the means of securing the electrical illuminating means to the lamp.

Fig. 4 is a detail view of a casing for supporting the electrical illuminating means and removed from the lamp.

Referring in detail to the drawing, the numeral 1 indicates as an entirety a miner's lamp of the carbide type consisting of the

water chamber 2 and carbide receptacle or chamber 3. The front of the water chamber 2 has formed thereon the usual reflector 4 provided with the burner 5. The rear wall of the chamber 2 has secured thereon a hook 6 for attaching the lamp to a miner's cap. The water chamber 2 in one side thereof is provided with a recess 7 in which is secured a casing 8 by means of fasteners 9. The casing 8 has a cover 9 hinged thereto as illustrated at 10 and secured to said casing at its free edge by a catch 11 so that said casing can be opened for the purpose of receiving an ordinary electrical flash light consisting of a battery 12, electric lamp 13 housed by a lens 14 and switch 15. The electrical flash light is of a well known type and the cover 9' is provided with a slot to permit the switch button 16 to extend therethrough whereby the circuit to the electric lamp 13 can be opened and closed from the exterior of the casing. The reflector 4 of the lamp 1 is provided with a cut-out portion in alignment with the recess 7 to receive the lens 14 and carries the partition 17 to prevent the heat from the burner 5 from effecting the electrical flash light within the casing or the lens 14.

From the foregoing description taken in connection with the accompanying drawings, it will be noted that means is provided whereby an ordinary electrical flash light can be installed on a carbide miner's lamp for the purpose of illumination when it is desired to refill the carbide chamber with carbide.

While I have shown and described the preferred embodiment of my invention, it will be understood that minor changes in construction, combination, and arrangement of parts may be made without departing from the spirit and scope of the invention as claimed.

Having thus described my invention, what I claim is:

1. A device of the character set forth including a miner's lamp of the carbide type having a recess in one side wall, a casing secured within said recess, a hinge cover for said casing, and electrical illuminating

means carried by said casing to be used for illumination when refilling the miner's lamp with carbid.

2. A device of the character set forth including a miner's lamp having a recess in one side thereof, a casing secured within said recess, an electrical flash light carried by said casing; said miner's lamp having an opening in its reflector to receive the lens of

the electrical flash light, and a partition disposed between the burner of the miner's lamp and electrical flash light.

In testimony whereof I affix my signature in presence of two witnesses.

SAM CASERTO.

Witnesses:

H. W. KARNES,
Wm. KING.
